[57] CLAIM

The ornamental design for a swimming pool leaf and debris removal net, as shown and described.

DESCRIPTION

FIG. 1 is a perspective of a swimming pool leaf and debris removal net embodying my new design;

FIG. 2 is a right side elevation thereof, with the left side elevation being a mirror image thereof;

FIG. 3 is a top plan thereof;

FIG. 4 is a right end elevation thereof;

FIG. 5 is a left end elevation thereof; and,

FIG. 6 is a bottom plan thereof.

The broken lines in FIGS. 1, 2, 4 and 5 represent stitches. The cross-hatching in the figures is fragmentarily shown for convenience of illustration, it being understood that the cross-hatching is uniformly continuous over the surface on which it appears.
